(57) **CLAIM**

The ornamental design for a cover for serving dish, as shown and described.

DESCRIPTION

This application is related to U.S. Ser. Nos. 29/855,759 and 17/961,503, filed Oct. 6, 2022, which are incorporated herein by reference.

FIG. 1 is a top, front and right side isometric view of a cover for serving dish showing our new design;

FIG. 2 is a bottom, rear and right side isometric view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof;

FIG. 8 is a rear elevation view thereof;

FIG. 9 is a cross-sectional view taken along line 9-9 of FIG. 3; and,

FIG. 10 is a cross-sectional view taken along line 10-10 of FIG. 3.

1 Claim, 5 Drawing Sheets
